FLOAT SWITCH

Harry A. Palmer, Malden, Mass., assignor to
 Palmer Inventions, Inc., a corporation of Massachusetts

Application May 12, 1933, Serial No. 670,801

1 Claim. (Cl. 200—84)

This invention relates to a float switch designed primarily for use in connection with a liquid feed regulating apparatus of that type for providing a constant feed or a constant gravity feed from a source of liquid supply to a point of destination or consumption, but it is to be understood that the switch, in accordance with this invention may be employed in any connection for which it is found applicable, and the invention 5 has for its object to provide, in a manner as hereinafter set forth, a float switch controlled by the liquid passing through the apparatus for controlling the power circuit of a liquid feed pump.

To the above ends and to others which may 10 hereinafter appear, the invention consists of such parts and such combination of parts which fall within the scope of the invention as claimed.

In the drawings:

Figure 1 is a vertical sectional view of a liquid feed regulating apparatus showing the adaptation therewith of a float switch in accordance 15 with this invention.

Figure 2 is a like view taken at right angles to Figure 1.

The apparatus, as shown, includes an annular housing 1 consisting of a body part 2 turned at its top, as at 3 for reinforcing purposes. The bottom of body part 3 has an internally arranged 20 annular flange 4 of angle-shape cross section. A bottom 5 is arranged within body part 2 and is formed with a depending flange 6 for seating in flange 4. The body part 2 between its transverse median and its upper end is inset circumferentially, as at 7 to provide a supporting ledge. Seated upon the latter, as well as being soldered 25 to body part 2 is a partition 8 formed with an axial opening 9. A flanged dome-shaped closure or top 10 is provided for the upper end of body part 2. Seated upon the partition 8 is a vertical 30 structure 11 formed from end to end with a guide passage 12 which registers with the bore 9. The upper portion of structure 11 is bifurcated diametrically thereof as at 13. Formed integral with opposite sides of the structure 11 and seated 35 upon the partition 8 is a pair of oppositely disposed lateral retainers 14 for the said structure 11. The retainers are of inverted T-shape in cross section and upwardly flanged at their outer ends, as at 15 which abut the inner face of body part 2. The retainers are detachably secured to body part 2 by holdfast means 16.

The partition 8 in connection with a portion of the body part 2 and closure 10 provides a closed chamber 17 for a switching mechanism 18 which 40 is pivotally mounted on a post 19 extended up-

wardly from one of the retainers 14. The mechanism 18 is formed with a lever arm 20 which extends through the furcation provided by the bifurcated upper portion of structure 11. The mechanism 18 preferably will be of the mercoind type and which is interposed in a power line circuit 21 employed in connection with driving a pump or other mechanism for forcing the liquid through a liquid feed line or for opening and closing a liquid source arranged above the apparatus. The circuit 21 is connected to the housing by a coupling 22 and extends therein to mechanism 18.

The partition 8 in connection with a portion of body part 2 and bottom 5 provides an upper 15 float or liquid receiving chamber 23 into which the supply section 23' of the liquid feed line opens. The bottom 5 is formed with spaced openings 24, 25 and 26, the latter being disposed at the center of bottom 5.

Surrounding the lower portion of body part 2 is a depending annular member 27 having an inturned bottom 28. The upper portion of member 27 is outset, as at 29 to provide an internal shoulder 30 upon which is seated a collar 31. The latter is secured to member 27 by holdfast means 32 and is soldered to body part 2.

Arranged within member 27 is an open top receptacle 33 providing a lower float or liquid receiving chamber 34, which opens at its bottom 30 into the delivery section 35 of the liquid feed line. The receptacle 33 has its top spaced from bottom 5 of chamber 23 and is spaced from member 27. Formed integral with the latter and the bottom 36 of receptacle 33 is a pair of intersecting oppositely disposed webs 37 for supporting receptacle 33 within member 27.

The feed line section 23' extends through member 27 adjacent receptacle 33, through opening 24 and upwardly into chamber 23 to a point 40 in proximity to partition 8. The upper terminal of section 23' is horizontally disposed, curved as at 38 and discharges downwardly. The section 23' is soldered to bottom 5.

Arranged within chamber 23, extending downwardly through opening 25, and opening into the upper portion of chamber 34 is an overflow pipe 39, for chamber 23. The pipe 39 is soldered to bottom 5.

Secured to bottom 5 and extending upwardly 50 through opening 26 is a ported, chambered, flanged casting 40 formed in its upper portion with a bore 41. The casting provides a valve housing. The ports and chamber in casting 40 are indicated at 42, 43 respectively. The bore 41 and 55

- ports 42 opening into chamber 43, and the lower part of the wall of the latter is beveled to provide a valve seat 44. The ports 42 and chamber 43 establish communication between chambers 23 and 34. Communication is controlled between said chambers by a valve 45 coacting with seat 44. Extending upwardly from valve 45 and through bore 41 is a valve stem 46. Depending from valve 45 is an inverted yoke 47.
- 10 The bottom 36 of receptacle 33 is provided with a pair of openings 48, 49 having secured therein depending nipples 50, 51 respectively. Attached to nipple 48 is an overflow pipe 48' for chamber 34 and a liquid carrying off pipe 52. Attached to nipple 49 is the delivery section 35 of the feed line.
- 15 Vertically movable in the chamber 23 by the liquid supplied to the latter is a float 53 for actuating the mechanism 18 to circuit opening and closing position. The float 53 is provided with a slotted stem 54 extending through the guide passage 12 of the said structure 11. The lever 20 extends through the slot 55 in stem 54. The length of slot 55 is such that when the level of 20 the liquid supplied to chamber 23 lowers to the line 56 the upper end wall 57 of slot 55 will engage and actuate lever 20 in a direction to provide for the operation of mechanism 18 in a manner to close the power circuit. When the 25 level of the liquid supplied to chamber 23 raises to the line 58 the lower end wall 59 of slot 55 will engage and actuate lever 20 in a direction to provide for the operation of the mechanism 18 in a manner to open the power circuit. During 30 the time that the power circuit is closed the chamber 23 will be supplied with liquid through feed line section 23'. During the time the power circuit is open the feed of liquid to chamber 23 will be discontinued.
- 35 40 Arranged within chamber 34 is a vertically movable float 59 for controlling valve 45 to maintain the liquid supplied to chamber 34 at a constant level resulting in a constant gravity feed through feed line section 35 to the point of des-

tination or consumption. The float 59 is formed with a stem 60 which is arranged within and is pivotally connected, as at 61 to the yoke 47. The constant level of the liquid within chamber 34 is indicated by the line 62. This level drops to 5 about .001" to provide for the liquid from chamber 23 which seeps past valve seat 44 maintaining a constant liquid level in chamber 34. The latter is of materially less area than chamber 23.

What I claim is:—

10 In a float switch for the purpose set forth, a vertically disposed stationary structure provided from end to end thereof with a guide passage, the upper portion of said structure being bi-furcated lengthwise thereof from its top edge and at diametrically opposed points thereof to form a pair of spaced paralleled furcations opening into said guide passage, a pair of oppositely extending horizontally disposed stationary inverted T-shaped post retainers merging at their inner ends into 15 said structure in proximity to the lower end of the latter, one of said retainers adapted to have one side of its base support adjacent to said structure a rockable power circuit controlling switch 20 of that type having a laterally disposed lever arm for extension through said furcations, a vertically movable float operated means traveling in the guide passage in and permanently depending from the said structure, said means being formed lengthwise of its upper portion with an elongated 25 rectangular slot through which is adapted to permanently extend said lever arm, the lower end of the wall of said slot adapted to engage the bottom edge of said lever arm on the upward movement of said means to elevate said lever arm for rocking said switch in a direction to open a power circuit, the upper end wall of said slot adapted to engage the top edge of said lever arm on the downward movement of said means to lower said lever for rocking said switch in a 30 direction to close the power circuit, and the base walls of said furcations providing stops adapted to arrest the lowering movement of said lever arm.

HARRY A. PALMER.
